UNITED STATES PATENT OFFICE

FRANCES JOHNSON, OF BROOKLYN, NEW YORK

DESIGN FOR A TEXTILE FABRIC OR SIMILAR ARTICLE OF MANUFACTURE

Application filed October 19, 1932. Serial No. 45,415. Term of patent 3½ years.

To all whom it may concern:

Be it known that I, FRANCES JOHNSON, a citizen of the United States, and resident of Brooklyn, in the county of Kings and State of New York, have invented a new, original, and ornamental Design for Textile Fabric or Similar Article of Manufacture, of which the following is a specification, reference being had to the accompanying drawing, forming a part thereof, and showing a face view of a piece of textile fabric embodying my design, the shading indicating contrast in color.

A repeat unit is contained within the lines A—A and B—B which unit is repeated over the surface of the fabric in the relation shown.

I claim:

The ornamental design for a textile fabric or similar article of manufacture substantially as shown and described.

Signed at New York, in the county of New York and State of New York, this eighteenth day of October A. D. 1932.

FRANCES JOHNSON.
